UNITED STATES PATENT OFFICE.

ADOLF FEINBLATT, OF NEW YORK, N. Y., ASSIGNOR OF ONE-HALF TO
SAM JASGUR, OF NEW YORK, N. Y.

MACHINE FOR MAKING LEATHER STRAPS AND BELTS.

No. 823,269.

Specification of Letters Patent.

Patented June 12, 1906.

Application filed December 23, 1905. Serial No. 293,061.

To all whom it may concern.

Be it known that I, ADOLF FEINBLATT, a subject of the King of Roumania, and a resident of New York, in the county and State of New York, have invented certain new and useful Improvements in Machines for Making Leather Straps and Belts, of which the following is a specification.

This invention has reference to improvements in machines for making leather straps and belts, and is particularly designed for making same by means of a single machine during one continuous operation.

It is the object of this invention to provide a machine by means of which finished straps and belts are made during one continuous operation.

The invention further consists in the construction and arrangement of parts and the combination of the devices for the various operations.

The invention is illustrated in the accompanying drawings, of which—

Figure 1 is a section on line 1-1 of Fig. 2 and represents in side elevation, partly in section, a machine which embodies my invention. Fig. 2 is a top plan view of the whole machine. Fig. 3 is a cross-section on line 3-3 of Fig. 1. Fig. 4 shows in detail a device for punching elongated holes, and Fig. 5 is a detail view of a guiding-roller.

Similar characters of reference denote like parts in all the figures.

The machine is mounted on substantial framework a a' a'' . On the top of the frame a there is a table b , which is repeatedly interrupted and cut out, so that various devices and rollers may be suitably mounted. The front portion b' of the table supports the hide when the operation begins. A pair of feed-rollers c c are provided here, which draw the hide in and move same forward. All hides are of irregular shape. Therefore the side ends must be cut off when straps are to be made. For this purpose two cutting-knives d d are mounted right behind the feed-rollers c c . These knives are secured to a hide-guiding device e e , which is mounted on two metal rods e' e' and adjustable thereon according to the width of the hides. The two rods are permanently fastened to the lower side portion of the frame a' . Near the rear end of

the adjustable guide e e there is another pair of feed-rollers f f . Then follows a small guiding-roller g , which keeps the hide down on the table when it is cut. It is rotated by the moving hide. Adjoining this guiding-roller there is a device for cutting the hide into straps. It consists of a small frame h and a number of blocks having each permanently secured thereto a knife i , which stands vertically up and slightly forward toward the hide. Small iron blocks are inserted between the knives and both are held together by tightening-screws located on the outside of the frame. The small blocks between the knife-blocks are of different width, whereby this device is made adjustable and adapted for cutting straps of various widths. A guiding-roller j is mounted in the frame near the strap-cutting device. As shown in detail in Fig. 5, it consists of an iron rod j' and a tube j'' , which carries thin guiding-disks j'' , arranged at such distance as is required for the width of the straps which pass between them. This roller is mounted in two slots j' in the frame a' , so that it is horizontally adjustable. A third pair of feed-rollers k is mounted in the frame to move the straps forward. All three pairs of feed-rollers are vertically adjustable, so as to suit the thickness of the leather. This is done by raising the top roller slightly, as indicated, on the set of rollers c c . The side parts of the frame a' have each a long slot j'' , in which three other guiding-rollers j'' j'' j'' are located. These are of the same construction as the roller j shown in detail in Fig. 5. All the guiding-rollers are turned by the moving leather straps and keep same down on the table. The straps when passing these rollers come in contact with the tube j'' , while the guiding-disks slide on the table. The part j' is the permanent part of these rollers, while the tubes with the disks may be exchanged for other tubes which have the disks at different distance, more or less of them, according to the desired width of the straps.

Near the rear end of the table b there is a pair of creasing-rollers l l' , of which the upper one is exchangeable, while the lower one is permanently mounted and smooth. The creasing-roller l consists of a shaft l^2 and a tube l^3 , on which the creasing appliances l^4

are provided. For straps of various widths different rollers are used, which have each the creasing appliances at a distance corresponding to the width of the straps desired.

5 The frame a carries the frame a' , whose middle portion rises upward, while the side parts extend throughout the entire length of the machine. A third frame a^2 is located on the middle portion of the frame a' . These 10 frames carry a device for punching the small round holes into the straps and three other devices, one for cutting off the acute angular front ends, and a second one for cutting off the rear ends of the straps, and a third one 15 for punching the long holes one in each strap near the rear end of same. The first device is operated alone, while the three other ones are operated simultaneously. The device for punching the round holes is located between 20 the feed-rollers k and the guiding-roller j^6 . The punches proper, m , are permanently secured in small blocks m' , which rest in a small frame m^2 . Small blocks m^3 of different width are placed between the punches. 25 The punch-supports m' are held firmly together by an angle-iron m^4 . A pin m^5 passes through the angle-iron. Each of its ends passes through a slot m^6 in the side of the frame a^2 and enters a cam n on either side of the machine. These cams are on a shaft o . Each 30 cam has a circular but eccentric recess n' , in which one end of the pin m^5 is located. When the cams turn, the pin m^5 is moved up and down in the eccentric recess, and when the 35 cam is down then the round holes are punched. During one revolution of the cams the punches descend once, and for a number of holes in each strap a corresponding number of revolutions by the cams has to 40 be made.

The elongated holes are made by a punching device. (Shown in detail in Fig. 4.) The punches proper, m^7 , have elongated cutting edges. This device is constructed like the 45 device for punching round holes. The punches proper are secured in blocks m^8 , which are located in a frame m^9 and have blocks m^{10} between for the purpose of adjusting them for the straps of various width. 50 These parts are held together sidewise by screws s . There is an angle-iron m^{11} and a small latch m^{14} thereon, which retain the blocks in position. The angle-iron m^{11} has on each side an uprising bar m^{12} with a shoulder m^{13} on each bar extending outwardly into a slot p in the frame a^2 . Two slots p' are in the top parts of the frame a^2 , one in each side, (see Fig. 2,) through which screws p^3 pass down into the shoulders m^{13} . Thus this 55 device is supported by the frame a^2 .

The device for cutting off the rear ends of the straps is constructed like the device for punching the long holes. One broad knife q is secured in a frame q^2 , and an angle-iron q^3 holds it down. Two small latches q' are lo-

cated on the front. The angle-iron has 70 rising bars q^4 , and the device is supported on the frame a^2 like the device punching the long holes. This cutting device is held on the frame a^2 by screws q^5 .

The device for cutting off the acute angular front ends of the straps is located in the rear portion of the machine between the guiding-roller j^8 and the creasing-rollers. The cutting-knives r are mounted on a frame r' 75 and held in position by a bar r^2 , suitably secured by screws r^3 . The uprising side bars r^4 have shoulders r^5 , which pass through lateral slots t in the rear portion of the frame a^2 . There are also two slots t' in the frame a^2 , (see 80 Fig. 2,) through which pass the screws r^6 down into the shoulders r^5 . It is seen that this device is also mounted on the frame a^2 . The knives r are of acute angular form and permanently mounted. For straps of another width the lower part is exchanged for one which is provided with knives at the corresponding distance from each other. 85

In the central top portion of the frame a' there is secured a pin or rod u , which extends 90 through openings in the sides of this frame and enters with one end on each side into a cam v . These cams are mounted on a shaft v' , which is supported in bearings v^2 . These are secured on the top of the frame a^2 . Thus 95 the frame a^2 and the three devices mounted thereon are operated together. The cams v are constructed like the cams n and have each an eccentric recess in which one end of the rod u is located. These cams therefore work 100 like the cams n . As the three devices for punching the elongated holes and cutting off the acute angular front ends and the rear ends are all supported by the frame a^2 , the same 105 are simultaneously actuated when the cams rotate.

The machine is preferably operated by power. Small machines, however, may be made which are operated by hand and foot power. The power is applied through the 110 pulley w , which is on the main shaft w' . This shaft carries a gear-wheel x and a sprocket-wheel y . Both are loose on the shaft. Between these two wheels a clutch z is mounted on the main shaft. The tooth-wheel x gears 115 with a tooth-wheel x' on the lower roller l' of the creasing device. The gear x' engages a gear x^2 , which is on the upper creasing-roller, whereby the creasing-rollers are turned. The shaft of the roller l' further carries a sprocket-wheel y' . Similar gears and sprocket-wheels are on the shafts of the feed-rollers. A chain passes over these sprocket-wheels y^2 y^3 y^4 on the lower feed-rollers k , f , and c , whereby the feed-rollers are turned. The main 125 shaft w' also carries a sprocket-wheel y^5 on its other end, which connects by a chain with a sprocket-wheel y^6 on a shaft o' . At the other end this shaft carries the gear x^5 and a clutch z' . The gear x^5 engages the gear x^6 , which is 130

on the shaft o of the cam n . By this arrangement the device for punching the round holes is operated. From the sprocket-wheel y a chain extends up to the sprocket y' on the shaft v' of the cams v , which are hereby operated.

Assuming now that power is applied to the pulley w , then the gear-wheel x on said shaft rotates the creasing and feed rollers. The hide will pass the side cutters $d d$ and the cutters i , which cut same into straps. When the straps come near the device for cutting the round holes, then the lever l^6 of the clutch z' is pulled, whereby the clutch enters the loose gear-wheel x^6 , which operated the gear x^6 on the shaft v of the cam n . By virtue of the pin m^6 , which reaches into the eccentric recess of the cam n , the device for punching round holes is operated. During one revolution the punches proper descend once and cut one hole each. For a number of holes in each strap the corresponding number of revolutions is necessary, and the lever of the clutch z' is pulled until the desired number of holes is cut into the straps. When the lever and clutch are released, then this device stops. As previously stated, the sprocket-wheel y' is loose on the main shaft. When the advancing straps come with their front ends near the device for cutting off the front ends, the clutch z is operated by pulling the lever l^6 . The clutch z , which was so far in the gear-wheel x and kept there by a spring z^2 , is drawn out. Hereby the feed mechanism is stopped because the gear x is also loose on the main shaft and the movement of the straps ceases. By pulling the lever the clutch enters the sprocket-wheel y , and the sprocket y' is rotated, which is on the shaft v' of the cams v . These move the pin or rod u up and down during one revolution, and thereby the frame a^2 is moved up and down with the devices for cutting off the rear ends and the acute angular front ends and the device for punching the elongated holes. These are thus operated simultaneously during one revolution of the cams v . Now the lever l^6 is released and the clutch enters the gear x again, whereby the feed mechanism is again operated. The straps move again. They pass the creasing device and drop out of the machine. As shown in the drawings in Figs. 1 and 3, the table b is provided with rubber plates below the punching and cutting devices. For making shorter straps the device for cutting off the front ends, which is located in the slots $t t'$, is simply moved inwardly, as well as the guiding-rollers $j^6 j^7 j^8$, which are in the slot j^6 . In a similar way the devices for cutting off the rear ends and for punching the long holes may also be adjusted in the slot p and accordingly the guiding-roller j in the slot j^4 .

In the described manner I have provided a leather strap and belt making machine by means of which straps and belts are made

with this single machine during one continuous operation.

Having thus described my invention, I claim as new and desire to secure by Letters Patent—

1. A machine for making leather straps and belts comprising framework, a table thereon, feed and guiding rollers mounted in said framework, two knives for cutting straight the sides of the hide, a plurality of knives for cutting the hide into straps, a device for punching round holes, a device for punching long holes, a device for cutting off the rear ends, a device for cutting the acute angular front ends, and a creasing device, all suitably mounted on the framework and so arranged that finished straps are made during one continuous operation.

2. A machine for making leather belts and straps comprising framework, feed and guiding rollers and a creasing device, a plurality of knives for cutting the hide into straps, and a device for cutting round holes into the straps means on said device for operating it independently, a separate top frame, a device for punching long holes one in each strap, a device for cutting off the rear ends of the straps, a device for cutting the acute angular front ends, all said three devices being mounted on the top frame, and means on said top frame for operating these three devices simultaneously.

3. A machine for making leather straps comprising framework, feed and guiding and creasing rollers therein, a device for cutting the hide into straps having knives which are adjustable as to their relative distance, a device for punching round holes into the straps having punches which are adjustable as to their relative distance, means on said device for operating it independently, a separate top frame, a device for punching long holes one in each strap having punches which are adjustable as to their relative distance, a device for cutting off the rear ends of the straps, and a device for cutting the acute angular front ends, and means on said top frame for operating these three devices simultaneously.

4. A machine for making leather straps comprising framework, feed and guiding and creasing rollers suitably mounted therein, an adjustable device for cutting the side ends of the hide and guiding the latter, an adjustable device for cutting the hide into straps, an adjustable device for punching round holes into the straps, an adjustable device for punching long holes one in each strap near the rear end of same adjustable in a horizontal plane, a device for cutting off the rear ends which is adjustable in a horizontal plane, and a device for cutting off the acute angular front ends also adjustable in a horizontal plane.

5. A machine for making leather straps comprising framework, feed and guiding and creasing rollers suitably mounted therein, an

adjustable device for cutting the side ends of the hide and guiding the hide so cut, a device for cutting the hide into straps having knives which are adjustable as to their relative distance, a device for punching round holes into the straps having punches which are adjustable as to their relative distance and adapted to be operated alone while the straps are moving, a top frame mounted on the frame-work, a device for punching long holes one in each strap having punches which are adjustable as to their relative distance, and a device for cutting off the rear ends of the straps, both last-named devices being adjustable horizontally as to their relative distance, and a device for cutting the acute angular front ends, all said three devices being mounted on the top frame and adapted to be operated simultaneously, and means on said frame for 20 adjusting the device for cutting the front

ends relative to its distance from the device for cutting off the rear ends.

6. In a machine for making leather straps an adjustable device for cutting the hide into straps so that straps of various widths may 25 be made, an adjustable device for punching round holes into the straps and adapted to be operated alone while the straps are moving so that any number of holes may be punched, and three devices adapted to be operated si- 30 multaneously, one for cutting off the rear ends; one for punching long holes, and one for cutting the acute angular front ends.

Signed at New York, N. Y., this 19th day of December, 1905.

ADOLF FEINBLATT.
